UNITED STATES PATENT OFFICE.

KARL ALBERT, OF WATHLINGEN, NEAR CELLE, GERMANY.

TOBACCO-BOX.

997,593.

Specification of Letters Patent. Patented July 11, 1911.

Application filed April 3, 1911. Serial No. 618,715.

To all whom it may concern:

Be it known that I, KARL ALBERT, a subject of the German Emperor, residing at Wathlingen, near Celle, in Germany, have 5 invented a certain new and useful Improvement in Tobacco-Boxes, of which the following is a specification.

The object of this invention is to provide a box for carrying rope-tobacco, with a device for conveniently cutting and removing plugs of tobacco therefrom.

The invention is illustrated in the accompanying drawing, in which—

Figure 1 is a plan-view of the box, with 15 lid removed, Fig. 2 an inside view of the lid, Fig. 3 a section on the line A—A of Fig. 1, Fig. 4 a section on the line B—B of Fig. 1, and Fig. 5 a plan-view of the lid, illustrating the cutting of the tobacco.

20 In the drawing *a* represents the box, *b* a spiral wall therein, and *c* the passage containing the rope-tobacco *d*. The part *e* is a sharp-edged shoe or wedge adapted to engage under the outer end of the tobacco

25 coil and lift the tobacco as shown in Fig. 4. The lid *f* has a flange *g* engaging over the edge *h* of the box, on which the lid is rotatable. The aperture *i* in the lid is closable by the shutter *k* pivoted at *l* inside the

30 lid. The tail *o* of the shutter forms a kind of pawl engaging an annular rack *p* with ratchet teeth fixed in the box to prevent rotation of the shutter during rotation of the lid in the direction indicated by the arrow

35 *u* in Fig. 1. On rotation of the lid in the direction indicated by the arrow *q*, the abutment *s* rotates the shutter with the lid, and the abutment *m* fixed to the shutter pushes the shoe *e* along the spiral passage. The

40 shoe in turn lifts the tobacco so that the end thereof protrudes through the aperture *i*. On rotation of the lid on the opposite direction the plug of tobacco is sheared off between the sharp edge *t* of the aperture and

45 the knife-edge *n* of the shutter, the latter being prevented from yielding, by the rack *p*.

What I claim as my invention and desire to secure by Letters Patent of the United States is:—

50 1. A tobacco-box comprising a spiral receptacle for a coil of rope-tobacco, an apertured rotatable lid on said receptacle, a wedge-device movable in said spiral receptacle and adapted to engage under and lift one end of the tobacco rope, and an abutment carried by the lid for moving said wedge-device so that the wedge lifts the rope-end through the lid-aperture. 55

55 2. A tobacco-box comprising a spiral receptacle for a coil of rope-tobacco, an apertured rotatable lid on said receptacle, a wedge-device movable in said spiral receptacle and adapted to engage under and lift one end of the tobacco rope, an abutment 60 carried by the lid for moving said wedge-device so that the wedge lifts the rope-end through the lid-aperture, and means for shearing off the lifted rope-end by rotation of the lid. 65

70 3. A tobacco-box comprising a spiral receptacle for a coil of rope-tobacco, an apertured rotatable lid on said receptacle, a wedge-device movable in said spiral receptacle and adapted to engage under and lift one end of the tobacco rope, a sharp-edged slide pivoted inside the lid, means preventing rotation of the slide with the lid in one direction, an abutment whereby the lid rotates the slide with it in the other direction, and an abutment fixed to the slide for moving the wedge-device so that the wedge lifts the rope-end through the lid-aperture, enabling the rope-end to be cut off by coaction 75 of the slide with an edge of the aperture 80 when the lid is rotated without the slide. 85

In witness whereof I have signed this specification in the presence of two witnesses.

KARL ALBERT.
